NONIONIC SURFACTANTS

Henry E. Fritz, Charleston, and Harry T. Zika and Edmund C. Steinle, Jr., South Charleston, W. Va., assignors to Union Carbide Corporation, a corporation of New York
 No Drawing. Filed Nov. 1, 1962, Ser. No. 234,835
 9 Claims. (Cl. 260—332.1)

This invention relates to a novel class of nonionic surfactants. More particularly, this invention relates to modified nonionic surfactants containing a sulfone-containing group which are characterized by reduced foam-forming tendencies. In another aspect, this invention relates to nonionic surfactants having lower cloud points than previously known nonionic surfactants and which are suitable for use as cold-water detergents.

Nonionic surface active agents or "surfactants" are well known to be relatively high molecular weight compounds consisting of a hydrophobic portion to which is attached a solubilizing group or hydrophilic element, containing groups such as ether links (—O—), hydroxyl groups (—OH—), carbonyloxy groups

carbamyl groups

and the like. With very few exceptions, the nonionic surfactants contain at least one hydroxyl group. These nonionic, hydroxyl-containing surfactants are widely employed as emulsifiers, wetting agents, penetrants, dye assistants, detergents and the like. Many of the nonionic, hydroxyl-containing surfactants exhibit a tendency to produce high, stable foams when in aqueous mixtures which are subject to agitation. This foam-forming tendency is often undesirable, particularly when the surfactant is employed as a laundry detergent. The foam cushions the agitation of the laundry in the modern automatic washing machines, thereby reducing the cleaning efficiency of the detergent.

It has now been found by this invention, however, that when the nonionic, hydroxyl-containing surfactant is reacted with an olefinically unsaturated sulfone, as hereinafter defined, the resulting compound has less tendency to form high, stable foams than the hydroxyl-containing surfactant, while retaining the ability to reduce surface tension and detergent properties of the hydroxyl-containing surfactant. In addition, the compounds of this invention have lower cloud points (the temperature at which an aqueous solution of the surfactant becomes cloudy on increasing the temperature of the solution). Thus, the nonionic surfactants of this invention are useful as "cold water detergents," and can be employed at temperatures at or slightly above room temperature. In addition to their outstanding utility as laundry detergents, the compounds of this invention can be employed as emulsifiers, wetting agents, penetrants, dye assistants and the like.

The nonionic, surface active agents of this invention generally consist of the residue of a nonionic, hydroxyl-containing, surface active compound bonded at the site of a hydroxyl group through the oxygen atom of said hydroxyl group to a β -hydrocarbylmonosulfone group. These compounds are represented by the general formula:

(I) $\text{ZfE}-(\text{Z})_m\text{J}_n$

wherein Z is the residue of an organic, nonionic, hydroxyl-containing, surface active compound containing n hydroxyl groups; E is a β -hydrocarbylmonosulfone group containing from 3 to 14 carbon atoms having a valence

of $m+1$ wherein the valence bonds are from carbon atoms; m is an integer having a value of from 0 to 1; and n is an integer having a value of at least 1, preferably from 1 to about 4, and is 1 when m has a value of 1.

By the phrase "residue of an organic, nonionic, hydroxyl-containing surface active compound containing n hydroxyl groups," as employed in the specification and appended claims, is meant that portion of the well-known hydroxyl-containing, nonionic, surface active compounds containing n hydroxyl groups, which remains after removal of a hydrogen atom from a hydroxyl group, and may be considered as being an organic radical having a valence of n whose valence bonds are from oxygen atoms bonded to carbon atoms.

By the phrase " β -hydrocarbylmonosulfone group having a valence of $m+1$ " is meant a monovalent or divalent group consisting solely of hydrogen, carbon and the divalent sulfonyl group (—SO₂—), wherein the sulfonyl group is bonded to two different carbon atoms and wherein the valence bonds are from a carbon atom β - to the sulfonyl group. In general, the β -hydrocarbylmonosulfone groups are represented by the formula:

wherein R¹, when taken alone, is a divalent alkylene group containing from 2 to 10, preferably from 2 to 4, carbon atoms wherein one valence bond is attached to the sulfonyl group, and the second valence bond is from an aliphatic carbon atom which is β - the sulfonyl group as ethylene, propylene, 1,2-butylene, 2,3-butylene, 1,2-hexylene, 2,3-hexylene, 3,4-hexylene, 1,2-octylene, 2,3-octylene, 3,4-octylene, 4,5-octylene and the like; R², when taken alone, is either R¹ or an alkyl group containing from 1 to about 10, preferably from 1 to 4, carbon atoms, such as methyl, ethyl, n-propyl, isopropyl, n-butyl, tert-butyl, iso-butyl, iso-pentyl, octyl, dodecyl, and the like, and R¹ and R², when taken together, form a trivalent saturated hydrocarbon chain containing from 3 to 14 carbon atoms, each of whose valence bonds is from a different carbon atom, two of such bonds being separated by at least 3 carbon atoms and being attached to the sulfonyl group, to form a cyclic ring having from 4 to 7 ring members, the third bond being from a carbon atom β - the sulfonyl group. As is apparent from the foregoing discussion, the hydrocarbylmonosulfone group can be in the form of a monovalent or divalent open chain structure or a monovalent heterocyclic structure containing the sulfonyl group. As examples of monovalent, open chain hydrocarbylmonosulfone groups one can mention 2-(methylsulfonyl)ethyl, 2-(ethylsulfonyl)ethyl, 2-propylsulfonyl)ethyl, 2-(iso-propylsulfonyl)ethyl, 2-(n-butylsulfonyl)ethyl, 2-(isobutylsulfonyl)ethyl, 2-(tert-butylsulfonyl)ethyl, 2-(octylsulfonyl)ethyl, 2-(dodecylsulfonyl)ethyl, 2-(methylsulfonyl)propyl, and the like. As examples of divalent, open-chain, hydrocarbylmonosulfone groups one can mention bis(dimethylene)sulfone, ethylene propylene sulfone, dipropylene sulfone, and the like. As examples of monovalent, heterocyclic hydrocarbylmonosulfone groups one can mention

3-thiethyl-1,1-dioxide,
 2-methyl-3-thiethyl-1,1-dioxide,
 3-methyl-3-thiethyl-1,1-dioxide,
 2,3,4-trimethyl-3-thiethyl-1,1-dioxide,
 2-ethyl-3-thiethyl-1,1-dioxide,
 2-propyl-3-thiethyl-1,1-dioxide,
 2-butyl-3-thiethyl-1,1-dioxide,
 3-tetrahydrothiophyl-1,1-dioxide,
 2-methyl-3-tetrahydrothiophyl-1,1-dioxide,
 3-methyl-3-tetrahydrothiophenyl-1,1-dioxide,
 4-methyl-3-tetrahydrothiophyl-1,1-dioxide,
 5-methyl-3-tetrahydrothiophyl-1,1-dioxide,

2,4-dimethyl-3-tetrahydrothiophyl-1,1-dioxide, 2,3,4,5-tetramethyl-3-tetrahydrothiophyl-1,1-dioxide, 5-ethyl-3-tetrahydrothiophyl-1,1-dioxide, 5-propyl-3-tetrahydrothiophyl-1,1-dioxide, 5-butyl-3-tetrahydrothiophyl-1,1-dioxide, 3-tetrahydrothiopyranyl-1,1-dioxide, 2-methyl-3-tetrahydrothiopyranyl-1,1-dioxide, 6-methyl-3-tetrahydrothiopyranyl-1,1-dioxide, 5,6-dimethyl-3-tetrahydrothiopyranyl-1,1-dioxide, 3-hexahydrothiopyranyl-1,1-dioxide, and the like.

Subgeneric to the compounds of Formula I are the compounds of the following formulae:

wherein Z , n and R^1 are as defined above; R^3 is an alkyl group containing from 1 to about 10 carbon atoms; and R^4 is a trivalent, saturated hydrocarbon chain containing from 3 to 14 carbon atoms, each of whose valence bonds is from a different carbon atom, two of such bonds being separated by at least 3 carbon atoms and being attached to the sulfonyl group to form a cyclic ring having from 4 to 7 ring members, the third bond being from a carbon atom β - the sulfonyl group.

Preferred β -hydrocarbylmonosulfone groups are the 3-tetrahydrothiophyl-1,1-dioxide groups of the formula:

wherein each R^5 is either hydrogen or alkyl of from 1 to about 4 carbon atoms, such as methyl, ethyl, propyl, isopropyl, n-butyl, sec.-butyl and tert.-butyl. In addition, 3-tetrahydrothiophyl-1,1-dioxide groups wherein each R^5 can be an alkoxy group of from 1 to 4 carbon atoms such as methoxy, ethoxy, propoxy and butoxy, or alkanoyloxy of from 2 to 4 carbon atoms such as acetoxy, propionoxy or butyroxy, can be employed and are fully equivalent to the β -hydrocarbylmonosulfonyl groups for the purposes of this invention.

As indicated above, the compounds of this invention are produced by the base-catalyzed reaction of a nonionic, hydroxyl-containing, surface active agent with an olefinically unsaturated sulfone. In this reaction, the hydroxyl group reacts with the olefinic double bond to produce an ether group, as illustrated by the reaction of a nonionic hydroxyl-containing surfactant with 2,5-dihydrothiophene-1,1-dioxide.

wherein Z and n are as defined above.

The nonionic, hydroxyl-containing surfactants employed in this reaction are well known compounds, and can be considered as consisting of a hydrophobic moiety chemically bonded to a hydrophilic moiety. In general, the hydrophobic moiety is the residue of an organic, hydrophobic compound containing at least one active hydrogen atom and the hydrophilic moiety is a saturated organic chain containing solubilizing groups such as ether oxygen, hydroxyl groups, carbonyloxy groups, carbamyl groups and the like, and containing at least one hydroxyl group. The hydrophilic moiety is bonded to the residue of the hydrophobic moiety at the site on the hydrophobic moiety occupied by said active hydrogen atom.

Although the β -hydrocarbylmonosulfone group present on the compounds of this invention is not employed for the purpose of additional hydrophilicity, it can be considered as composing a portion of the hydrophilic moiety of the compounds of this invention. Thus, the compounds of this invention can be further considered as consisting of a hydrophobic moiety chemically bonded to a hydrophilic moiety, wherein the hydrophobic moiety is the residue of an organic hydrophobic compound containing at least one active hydrogen atom, said hydrophobic moiety being bonded at the site of said active hydrogen atom to a hydrophilic moiety consisting of the residue of a hydroxyl-containing hydrophilic chain bonded through the oxygen atom of a hydroxyl group to a β -hydrocarbylmonosulfone group.

The nonionic, hydroxyl-containing surfactants employed in producing the compounds of this invention can be classified generally according to the structure of the hydrophilic moiety of the compound. The great bulk of these surfactants have as the hydrophilic moiety one or more chains containing one or more alkyleneoxy groups, and have the general formula

wherein Y is the residue of an organic hydrophobic compound containing y active hydrogen atoms; y is an integer having a value of at least 1, generally from 1 to about 6 and preferably from 1 to about 4; X is an alkyleneoxy chain; and H is a hydrogen atom bonded to an oxygen atom of said alkyleneoxy chain.

By the term "residue of an organic hydrophobic compound containing y active hydrogen atoms" is meant that portion of a hydrophobic compound having y active hydrogen atoms which remains after the active hydrogen atoms have been removed, and thus, is an organic radical, or group of atoms, having a valence of y .

By the term "alkyleneoxy chain," as employed in the specification and claims, is meant a chain containing one or more alkyleneoxy groups. By the term "alkyleneoxy group" as employed in the specification and claims, is meant a divalent alkylene group, such as methylene, ethylene, propylene, butylene, styrene ($-CH_2CH(C_6H_5)-$), and the like; bonded to an oxygen atom in a manner such that one of the valences of the alkyleneoxy group is from an oxygen atom and the other is from a carbon atom. As examples of alkyleneoxy groups one can mention methyleneoxy ($-CH_2O-$), ethyleneoxy ($-C_2H_4O-$), propyleneoxy, ($-C_3H_6O-$), butyleneoxy ($-C_4H_8O-$), styreneoxy ($-C_2H_5(C_6H_5)O-$) and the like.

By the term "active hydrogen atom" is meant a hydrogen atom which reacts with methyl magnesium iodide to produce methane in the well-known Zerewitinoff reaction (Niederl and Niederl, "Micromethods of Quantitative Organic Analysis," p. 263, John Wiley & Sons, New York city, 1949). Active hydrogen atoms of this type are normally members of a functional group containing an oxygen atom, for example, hydroxyl, whether bonded to an aliphatic or aromatic carbon, a carboxyl group, a phosphinico group ($>P(O)OH$), and the like; a nitrogen atom, such as amino, imino, amido, hydrazino, hydrazo, guanido, guanyl, sulfonamido, ureido, thioureido and the like; or a sulfur atom, such as mercapto, thiocarboxyl, and the like. In addition, a hydrogen atom may be activated by proximity to a carbonyl group, as in cyanoacetic esters, acetoacetic esters, malonic esters and the like.

As examples of suitable hydrophobic active-hydrogen-containing compounds which can be employed in producing the nonionic surfactants of the type represented by the Formula VI one can mention:

(1) Saturated and unsaturated aliphatic and cycloaliphatic carboxylic acids, particularly those acids having from about 7 to about 25 carbon atoms, such as enanthic acid, caprylic acid, capric acid, heptadecanoic acid, lauric acid, palmitic acid, stearic acid, oleic acid, linoleic acid,

linolenic acid, eleostearic acid, abietic acid and the like.
(2) Dialkyl esters of phosphoric acid of the formula

wherein each R is alkyl of from 6 to 12 carbon atoms, such as bis(hexoxy) phosphonic acid, bis(2-ethylhexoxy)-phosphonic acid, bis(dodecoxy) phosphoric acid, and the like.

(3) Alkylated phenols, particularly those containing from about 4 to about 22 carbon atoms in the alkyl group thereof, for example, butylphenol, amylphenol, hexylphenol, octylphenol, nonylphenol, dodecylphenol, nonadecylphenol, and the like. These compounds are normally the para-isomer, although some ortho-isomers may be present in the commercially obtainable product. In addition, one can employ complex phenols, such as those obtained by the condensation of phenol with an aldehyde or a ketone. An example of this type of compound is the condensation product of alkylcyclohexanone and phenol having the formula:

(4) Aliphatic and cycloaliphatic alcohols containing from about 8 to about 22 carbon atoms, such as octyl alcohol, nonyl alcohol, decyl alcohol, "coco" alcohol (a mixture of C₁₀ to C₁₆ alcohols), lauryl alcohol, oleyl alcohol, tallow alcohol (a mixture of C₁₆ to C₁₈ alcohols), cetyl alcohol, stearyl alcohol, hydroabietyl alcohol, tri-decyl alcohol, 2,6,8-trimethyl-4-nonyl alcohol, eicosanyl alcohol linoleyl alcohol, octylcyclohexanol, 9-phenylstearyl alcohol, 10-phenylstearyl alcohol and the like. Polyhydric alcohols can also be employed, for example sorbitol glucosides of alkylphenols or mono fatty acid esters of anhydrosorbitols, fatty acid derivatives of trimethylolaminomethane of the formula

the reaction product of stearic hydroxide and glycidol of the formula

and the like.

(5) Alkyl mercaptans having from about 8 to about 22 carbon atoms, such as octyl mercaptan, nonyl mercaptan, decyl mercaptan, dodecyl mercaptan, eicosyl mercaptan and the like.

(6) Fatty acid amides having from 5 to about 20 carbon atoms, such as capramide, lauramide, "coconut" oil amides, oleamide, myristamide, stearamide and the like.

(7) Hydrophobic alkylene-oxide polymers consisting of the residue of an organic compound containing at least one active hydrogen atom, preferably from 1 to about 6 active hydrogen atoms, bonded at the side of said active hydrogen atom to an alkyleneoxy chain having an atomic ratio of carbon to oxygen of at least 2.75, generally from 2.75 to about 8, and preferably from 3 to about 4. The alkyleneoxy chains usually contain propyleneoxy units, either alone or in combination with ethyleneoxy units or butyleneoxy units, although styreneoxy units

have also been employed. The specific composition of these hydrophobic alkylene oxide polymers will vary widely depending upon the nature of the residue of the active hydrogen-containing compound, i.e., whether it is

hydrophilic or hydrophobic, and the nature of the alkyleneoxy group. In general, the more carbon atoms present in the alkyleneoxy group, the fewer alkyleneoxy groups are necessary in an alkyleneoxy chain to produce a hydrophobic polymer.

For example, to be hydrophobic, a polymer produced by the reaction of butanol with propylene oxide must have an average molecular weight of at least about 450, whereas a polymer produced by the reaction of butanol and butylene oxide is hydrophobic at a molecular weight of only 350.

As examples of suitable active hydrogen-containing compounds one can mention methanol, butanol, formic acid, acetic acid, butanoic acid, diethyl amine, ethyl butylamine, methyl acetamide, methyl mercaptan, butyl mercaptan, N-propyl ethanesulfonamide, ethylene glycol, 1,3-butylene glycol, 1,5-pentanediol, sucrose, glycerine, resorcinol, oxalic acid, glycolic acid, acetamide, benzene sulfonamide, ethanolamine, diethanolamine, triethanolamine, butylamine, aniline, ethylene diamine, diethyl malonate and the like.

20 The hydrophilic alkyleneoxy chain represented by —X— in Formula VI above, is generally an ethyleneoxy chain, or a chain composed of a mixture of ethyleneoxy units and either methyleneoxy units or propyleneoxy units, wherein the atomic ratio of carbon to oxygen is from

25 about 1.5:1 to about 2.1:1. The ethyleneoxy units are employed for hydrophilicity, and the methyleneoxy and propyleneoxy units, although not hydrophilic in nature, are employed to modify the character of the hydrophilic alkyleneoxy chain. The length of the alkyleneoxy chain

30 will vary depending upon the nature of the hydrophobic moiety and the properties desired in the resultant surfactant. In general, greater water solubility is obtained as the number of ethyleneoxy units increases. When the hydrophilic moiety is a poly(ethyleneoxy) chain, the most useful products are obtained when the molecular weight of the poly(ethyleneoxy) chain is from about 25 to about 35 900 percent of the molecular weight of the hydrophobic moiety.

35 The surface active compounds of Formula VI can be further classified according to the number of alkyleneoxy groups in the alkyleneoxy chain; i.e., whether the alkyleneoxy chain contains only one alkyleneoxy group or whether it is a poly(alkyleneoxy) chain.

The surfactants having only one alkyleneoxy group in the alkyleneoxy chain are exemplified by the alkanolamide condensates, produced by the reaction of a fatty acid with diethanolamine.

50 The surfactants having poly(alkyleneoxy) chains are generally produced by the reaction of an active hydrogen-containing hydrophobe with ethylene oxide, wherein the alkyleneoxy chain consists of a series of ethyleneoxy groups (—C₂H₄O—), usually from about 4 to about 50 ethyleneoxy groups. Heteric poly(methyleneoxy)-poly(ethyleneoxy) chains can be produced, for example, by the reaction of an active hydrogen containing hydrophobic compound with formaldehyde and either ethylene glycol or ethylene oxide, and the heteric poly(ethyleneoxy)-poly(propyleneoxy) chains can be produced by the reaction of an active-hydrogen-containing, hydrophobic compound with a mixture of ethylene oxide and propylene oxide.

65 Poly(ethyleneoxy) chains can also be formed from polyethylene glycols by the reaction of the active-hydrogen-containing hydrophobe with the glycol.

The second broad class of hydroxyl-containing nonionic surfactants are partial ethers or partial esters of polyhydric alcohols other than ethylene glycol or polyethylene glycol. As examples of compounds of this type one can mention

(1) Fatty acid partial esters of sorbitans (anhydrosorbitols), such as 2-(hydroxymethyl)3,4,5-trihydroxytetrahydropyran, 2-(1',2'-dihydroxyethyl)-3,4-dihydroxytetra-

hydrofuran, 3,6-dihydroxyhexahydrofuro[3,2-b]furan and the like.

(2) Low molecular weight alkylmethylolphenol esters of glucose or sorbital. For example, amyl- or hexylphenol, when hydroxymethylated and reacted with sorbital, gives a somewhat water soluble compound of the formula

10

(3) Glucosides of hydrophobic alcohols and phenols.

(4) Reaction products of a fatty acid, usually a coconut fatty acid, with trimethylolaminomethane or bis(hydroxypropyl)amine.

(5) Higher fatty acid partial esters of pentaerythritol or dipentaerythritol.

(6) Monoethers of 1,2-dihydroxycyclohexane produced by the reaction of a fatty alcohol with cyclohexene oxide

(7) Products produced by the reaction of glycidol with an active hydrogen containing compound, usually an acid amide, a sulfonamide, or a N-(hydroxyethyl) amide.

It is emphasized that the foregoing discussion is not intended to be limiting as to the scope of this invention with regard to the nonionic, hydroxyl-containing surfactants contemplated by this invention. Rather, it is intended to be illustrative of the wide range of the known nonionic, hydroxyl-containing, surface active compounds which can be employed in producing the compounds of this invention.

The olefinically unsaturated sulfones which are employed in producing the compounds of this invention contain one sulfonyl group ($-\text{SO}_2-$) whose valences are satisfied by bonds to two different carbon atoms, either by way of two monovalent saturated or mono-olefinically unsaturated hydrocarbon groups, or by a divalent alkenylene hydrocarbon group, the total number of carbon atoms in said unsaturated sulfone being from 3 to about 14, wherein the olefinic double bonds are activated by proximity to the sulfonyl group. In general, suitable unsaturated sulfones are those having a double bond that is α,β or β,γ to the sulfonyl group. Although we do not wish to be bound by theories, it is believed that, for the reaction of the hydroxyl-containing surfactant with the unsaturated sulfone to occur, there must be a conjugated double bond system; and that the reactive species is a compound having a double bond α,β to the sulfonyl group. However, it has been found that a sulfone having a double bond β,γ to the sulfonyl group, when heated in basic medium, will isomerize to form the α,β -unsaturated sulfone. Regardless of theory, however, α,β - and β,γ -unsaturated sulfones are suitable for use in producing the compounds of this invention. These sulfones are represented by the formula:

wherein G, when taken alone, is a monovalent alkenyl group containing from 2 to 10, preferably 2 to 4 carbon atoms, such as vinyl, allyl, propenyl, 1,2-octenyl, and the like; G¹ when taken alone, is either an alkyl group having from 1 to 10, preferably 2 to 4, carbon atoms or an alkenyl group having from 2 to 10, preferably 2 to 4, carbon atoms; and G and G¹, when taken together, form a divalent alkenylene group of from 3 to about 14 carbon atoms which when taken with the sulfonyl group forms a heterocyclic ring having from 4 to 7 ring members, and wherein the olefinic double bond is α,β - or β,α - to the sulfonyl group.

Subgeneric to the compounds of the Formula VII are the cyclic sulfones of the formula

(VIII)

and the acyclic sulfones of the formula

(IX)

wherein R⁶ is a divalent alkenylene group containing from 3 to about 14 carbon atoms which, when taken with the sulfonyl group, forms a heterocyclic ring having from 4 to 7 ring members; each R⁷, when taken individually, is hydrogen or alkyl of from 1 to 4 carbon atoms; R⁸ is a divalent alkylidene group, i.e., a methylene group or an alkyl-substituted methylene group containing from 1 to 5 carbon atoms; x is an integer having a value of 0 or 1; and R⁹ is an alkyl group or an alkenyl group of from 1 to about 10 carbon atoms, preferably from 1 to 4 carbon atoms.

As examples of the cyclic sulfones of Formula VIII one can mention thietene-1,1-dioxide, 2-methylthietene-1,1-dioxide, 3-methylthietene-1,1-dioxide, 4-methylthietene-1,1-dioxide, 2,3-dimethylthietene-1,1-dioxide, 2,4-dimethylthietene-1,1-dioxide, 2,3,4-trimethylthietene-1,1-dioxide, 4-ethylthietene-1,1-dioxide, 4-propylthietene-1,1-dioxide, 4-butylthietene-1,1-dioxide, 2,3,4-tributylthietene-1,1-dioxide, 2,5-dihydrothiophene-1,1-dioxide, 2,3-dihydrothiophene-1,1-dioxide, 2-methyl-2,5-dihydrothiophene-1,1-dioxide, 3-methyl-2,5-dihydrothiophene-1,1-dioxide, 3,4-dimethyl-2,5-dihydrothiophene-1,1-dioxide, 3-ethyl-2,5-dihydrothiophene-1,1-dioxide, 3-propyl-2,5-dihydrothiophene-1,1-dioxide, 3-butyl-2,5-dihydrothiophene-1,1-dioxide, 3,4-dihydro-2H-thiapyran-1,1-dioxide, 3,6-dihydro-2H-thiapyran-1,1-dioxide, 2,3-dihydro-4H-thiapyran-1,1-dioxide, 2-methyl-3,4-dihydrothiapyran-1,1-dioxide, 6-methyl-3,4-dihydrothiapyran-1,1-dioxide, 5,6-dimethyl-3,4-dihydrothiapyran-1,1-dioxide, 2-methyl-3,6-dihydrothiapyran-1,1-dioxide, 4-methyl-3,6-dihydrothiapyran-1,1-dioxide, 2,3,4,5-tetrahydrothiapyran-1,1-dioxide, 2,3,4,7-tetrahydrothiapyran-1,1-dioxide and the like.

As examples of acyclic sulfones of the Formula IX one can mention divinyl sulfone, vinyl methyl sulfone, vinyl ethyl sulfone, vinyl propyl sulfone, vinyl butyl sulfone, vinyl undecyl sulfone, vinyl dodecyl sulfone, diallyl sulfone, allyl methyl sulfone, allyl ethyl sulfone, allyl undecyl sulfone, propenyl methyl sulfone, propenyl ethyl sulfone, propenyl undecyl sulfone and the like.

It should be noted that 2,5-dihydrothiophene-1,1-dioxide and its isomer, 2,3-dihydrothiophene-1,1-dioxide, exist in an equilibrium mixture under the reaction conditions employed for their condensation with the nonionic hydroxyl-containing surfactant. However, this does not affect the position of addition of the surfactant residue, which in either case is on the carbon atom β to the sulfonyl group.

It should be further noted that certain sulfone-containing compounds have previously been employed as surface active agents. As examples of these compounds one can mention the sulfonated tetrahydrothiophyl-1,1-sulfones disclosed in U.S. Patent 2,452,949, the tetrahydrothiophyl-1,1-dioxide esters of long chain fatty acids disclosed in U.S. Patent 2,451,299, the 3-tetrahydrothiophyl-1,1-dioxide laurimide disclosed in U.S. Patent 2,743,236, and tert-octyl- β -hydroxyethyl sulfone. However, the sulfonyl group in these known compounds is employed as the hydrophilic portion of the surface active compound. In the compounds of this invention, however, particularly, those produced from nonionic surfactants having poly(ethyleneoxy) chains as the hydrophilic portion of the surfactant, the hydrophilic properties of the sulfonyl group are negligible when compared with the balance of the hydrophilic portion of the compound. In fact, the β -hydrocarbylmonosul-

fone group is hydrophobic in nature, as is evidenced by the reduced cloud points of the compounds of this invention as compared with the cloud points of the parent, hydroxyl-containing, surface active compound. The reduction of cloud point clearly is caused by a decrease in solubility or hydrophilicity resulting from the addition of the β -hydrocarbylmonosulfone group. Unexpectedly and surprisingly, however, the adduct retains the detergency and wetting characteristics of the hydroxyl-containing, surface active compound from which it is derived. Thus, sulfones employed in producing the compounds of this invention are employed to reduce the solubility of known surface active compounds, while at the same time providing a low-foaming, surface active compound having excellent wetting and detergent characteristics.

The mole ratio of hydroxyl-containing surfactant to unsaturated sulfone in the reaction mixture is not particularly critical. However, because of the difficulty of removal of unreacted hydroxyl-containing surfactant from the reaction product, it is preferred to employ a molar excess of unsaturated sulfone, generally from about 2 to about 5 moles of sulfone per molar equivalent of hydroxyl group on the nonionic surfactant.

As has already been indicated, the reaction is catalyzed by basic substances. Examples of suitable basic catalysts include alkali metal hydroxides, such as lithium hydroxide, sodium hydroxide, potassium hydroxide, rubidium hydroxide, or cesium hydroxide; organic quaternary ammonium bases such as benzyltrimethylammonium hydroxide and the like; alkali metal alkoxides, such as sodium methoxide and the like; or an alkali metal, particularly sodium or potassium. The choice of catalyst depends primarily on the desired color of the product. When the alkali metal hydroxides are employed the product usually is dark in color. Lighter colored products are obtained with organic quaternary ammonium bases, but the product often has an ammoniacal odor. Still lighter products are obtained when sodium metal or potassium metal is employed as the catalyst. The catalytic amount of base employed is not narrowly critical. However, it has been found that from about 0.01 to about 0.5 or more molar equivalent of base per molar equivalent of nonionic surfactant hydroxyl group provides reasonable reaction rates.

The reaction is normally conducted at temperatures of from about 50° C. to about 90° C., with temperatures of from about 65° C. to about 75° C. being preferred. The lower reaction temperature is not particularly critical, and temperatures of less than 50° C. can be employed if desired. However, the reaction rate is too low at these temperatures for reasonable production rates. The maximum specified temperature of 90° C., like the lower temperature limit, is not narrowly critical, and higher temperatures can be employed if desired, depending upon the particular unsaturated sulfone employed in the reaction. The unsaturated sulfones, particularly 2,5-dihydrothiophene-1,1-dioxide and its alkyl-substituted derivatives are unstable at elevated temperatures, decomposing to form sulfur dioxide and a conjugated diolefin. Although the decomposition may occur at various temperatures (see for example, D. Craig, JACS, 65, 1006 (1943)), all of the sulfones are quite stable at reaction temperatures of about 90° C. or less and there is little chance of loss of sulfone due to decomposition at these temperatures.

The reaction time is not critical and will vary widely depending upon the reaction temperature and the amount of sulfone employed in the reaction. In general, reaction times of at least 6 hours and often of up to about 24 hours or more are required to achieve suitable conversions of hydroxyl-containing surfactant to the sulfonyl ethers of this invention.

The reaction is preferably conducted under an inert, e.g., nitrogen, atmosphere because in many cases, the presence of oxygen tends to cause a discolored product.

Solvents or diluents are unnecessary because excess sulfone provides a suitable reaction medium. However, inert

liquid organic compounds such as ethers, dioxanes, aromatic hydrocarbons, tetrahydrothiophene-1,1-dioxide and the like can be employed if desired.

The compounds of this invention are readily recovered by procedures known to the art. When the sulfone employed as a reactant is unstable at elevated temperatures, it can be removed by heating the reaction product at elevated temperatures and removing the sulfur dioxide and diene produced by the decomposition. In some cases the hydroxyl-containing nonionic surfactant employed as a reactant can be removed by a salting-out technique wherein calcium chloride is admixed with the reaction product to form an insoluble complex with the hydroxyl-containing compound. This complex precipitates out of the reaction mixture and can be removed by conventional separation procedures, such as filtration, decantation and the like.

A preferred procedure for producing the compounds of this invention when the nonionic, hydroxyl-containing surfactants of Formula VI above, are employed, particularly those having poly(alkyleneoxy) chains having at least 4 alkyleneoxy groups in the poly(alkyleneoxy) chains, comprises adding the selected unsaturated sulfone directly to the mixture from the reaction of the active-hydrogen-containing hydrophobe with ethylene oxide. This reaction is often a base-catalyzed reaction, and the catalyst for the reaction of the ethylene oxide and the hydrophobe can be employed to catalyze the reaction of the hydroxyl group with the sulfone.

The reaction product, even after use of recovery procedures such as those outlined above, normally contains some unreacted hydroxyl-containing surfactant because, even at high concentrations of unsaturated sulfone in the reaction mixture, it is difficult to obtain complete reaction with the hydroxyl groups, and as alluded to above, the removal of the unreacted hydroxyl-containing compound from the reaction product is very difficult. However, products containing amounts of unreacted hydroxyl-containing surfactant as high as 40 mole percent or more, based on total product, as determined by analysis for hydroxyl group, still have greatly reduced foaming tendencies and cloud points when compared with the surfactant from which they derived, and are eminently suited for use as detergents, wetting agents and the like. Thus, the compositions of this invention can be more broadly defined, as being compositions consisting of the residue of a nonionic, hydroxyl-containing, surface active compound containing n hydroxyl groups bonded through at least 0.6 n oxygen atoms at the site of said hydroxyl groups to a β -hydrocarbylmonosulfone group. Compositions containing at least 75 percent of reacted hydroxyl group are preferred, with composition having 90 percent or more reacted hydroxyl group being most preferred. As is apparent, this definition does not refer to a specific compound, rather, it refers to an admixture of compounds in terms of a theoretical compound representing the average composition of the admixture. The formula for this theoretical compound is:

wherein M is a residue of an organic hydroxyl-containing, surface active compound containing p hydroxyl groups; p is an integer having a value of at least 1, usually from 1 to 6 and preferably from 1 to about 4; J is a β -hydrocarbylmonosulfone group as defined above; and q is a number having a value of greater than 0 but not greater than p , and preferably has a value of from about 0.6 p to p , preferably 0.75 p to p , and most preferably from 0.9 p to p .

The following examples are illustrative. The tests employed to evaluate the products of the examples are as follows:

(1) *Ross-Miles foam test*.—Determined according to ASTM D-1173-53, employing a concentration of 0.2 weight percent of surfactant in distilled water at a temperature of 50° C. Reported as the foam height in centi-

meters immediately after agitation and after standing for 5 minutes.

(2) *Surface tension*.—Determined according to ASTM D-1331-54T, employing a Du Nuoy tensiometer and a concentration of 0.05 weight percent surfactant in distilled water at 25° C. Reported in dynes/centimeter.

(3) *Relative detergency*.—Determined with a "Terg-o-Tometer" according to the procedure of J. C. Harris, "Detergency Evaluation and Testing," p. 98, Interscience Publishers, Inc., 1954. Four 6 x 6 inch standard soiled swatches supplied by U.S. Testing Company were washed for 10 minutes at 120° F., and 120 cycles per minute, employing a solution of 0.2 weight percent surfactant in distilled water. After hand wringing, power-rinsing for 5 minutes in distilled water and drying by ironing, the reflectance of each swatch was determined with a Model 610 Photovolt Reflection Meter equipped with a green tristimulus filter and a wide angle scanner. The reflectometer was calibrated at 100 using several thicknesses of white bond paper. Relative detergency was calculated by dividing the reflectance obtained from the surfactant-washed swatches by reflectance obtained from a swatch washed with a solution containing 0.2 weight percent "Ivory" flakes in water and is reported in percent.

(4) *Draves wetting test*.—Determined at 25° C. according to the procedure described in the 1960 Technical Manual of the American Association of Textile Chemists and Colorists, vol. 36, p. 160, employing 5-gram standard skeins supplied by Test Fabrics Inc. Reported as the concentration in grams of detergent/liter of distilled water required for a wetting time of 20 seconds.

(5) *Cloud point*.—Determined from a 0.5 weight percent solution of surfactant in distilled water, and is the temperature at which the solution, on raising the temperature, becomes milky or hazy.

Example 1

A mixture containing 600 grams (1.18 moles) of a nonylphenol-ethylene oxide adduct containing an average of 9 ethyleneoxy groups in a poly(ethyleneoxy) chain, 236 grams (2.0 moles) of 2,5-dihydrothiophene-1,1-dioxide and 10 grams (0.185 mole) of sodium methoxide was heated at 68° C., with stirring and under a nitrogen atmosphere, for 5.5 hours. At this time 7 grams of 85 percent phosphoric acid was added and the mixture was heated at 68° C. for 1 hour to neutralize the catalyst. The reaction mixture was then heated at 115° C. for 6 hours at 1 mm. mercury pressure to decompose the unreacted 2,5-dihydrothiophene-1,1-dioxide. After cooling the reaction mixture to room temperature and filtering there was recovered 590 grams of product which contained 66.5 weight percent of the 3-[nonylphenoxy]tetrahydrothiophene-1,1-dioxide, 16.5 weight percent unreacted nonylphenol-ethylene oxide adduct and 17 weight percent unreacted dihydrothiophene-1,1-dioxide. The properties of this product as determined by the above-described tests are tabulated below, together with the results of equivalent tests conducted on samples of the nonylphenoxyethylene oxide adduct employed in producing the product of this invention.

	Foam Height, mm.		Relative Detergency, Percent	Wetting Test, gm./l.	Cloud Point, °C.
	Initial	After 5 min.			
Product--Control--	1.80 1.160	3 50	31.5 29.2	114 116	0.68 0.68
					42.2 55.8

¹ Measured at 40° C. because of reduced cloud point.

From the foregoing table it is readily apparent that the compositions of this invention have greatly reduced foaming tendencies and cloud points when compared with the parent hydroxyl-containing surfactant, without a significant change in wetting or detergency properties, even

at concentrations of the sulfone-containing surfactant of this invention in the detergent composition as low as 66 weight percent.

Example 2

5 A mixture of 495 grams (0.75 mole) of a nonylphenol-ethylene oxide adduct containing an average of 10.5 ethyleneoxy groups in a poly(ethyleneoxy) chain, and 1 gram (0.0435 gram atom) of metallic sodium was heated at 100° C., with stirring under a nitrogen atmosphere for 10 hours. The reaction mixture was cooled to 65° C. and 266 grams (2.25 moles) of 2,5-dihydrothiophene-1,1-dioxide was added. The resulting mixture was maintained at 55 to 70° C. for 24 hours, after which time it was cooled to room temperature, admixed with 2.5 liters of ethyl ether and filtered. The filtrate was flash distilled to remove the ethyl ether and vacuum dried to recover 640 grams of product.

20 A 200-gram sample of the product was heated at 120° C. for 2.5 days at 0.1 mm. pressure to decompose unreacted 2,5-dihydrothiophene-1,1-dioxide. There was recovered 179 grams of a product containing 74.4 weight percent 3-[nonylphenoxy]tetrahydrothiophene-1,1-dioxide, 10.4 weight percent unreacted nonylphenol-ethylene oxide adduct, and 15.2 weight percent unreacted dihydrothiophene-1,1-dioxide.

25 The properties of this product and of the nonylphenol-ethylene oxide adduct are tabulated below.

30	Foam Height, mm.		Surface Tension, dynes/cm.	Relative Detergency, Percent	Wetting Test, gm./l.	Cloud Point, °C.
	Initial	After 5 min.				
35 Product--Control--	1.85 1.190	10 10	31.5 29.8	114 112	0.55 0.70	49.0 63.5

¹ Measured at 45° C. because of reduced cloud point.

Example 3

40 Employing procedures similar to those described in Example 2, 3700 grams (5.42 moles) of the nonylphenol-ethylene oxide adduct employed in Example 2, 1875 grams (15.9 moles) of 2,5-dihydrothiophene-1,1-dioxide and 10 grams (0.435 gram atom) of sodium, was heated at 60 to 45 61° C. for 6 hours. There was recovered 5205 grams of product which contained 94.5 weight percent 3-[nonylphenoxy]tetrahydrothiophene-1,1-dioxide, 3.5 weight percent unreacted nonylphenol-ethylene oxide adduct and 1.9 weight percent unreacted dihydrothiophene-1,1-dioxide.

50 The properties of this product and of the nonylphenol-ethylene oxide adduct are tabulated below.

55	Foam Height, mm.		Surface Tension, dynes/cm.	Relative Detergency, Percent	Wetting Test, gm./l.	Cloud Point, °C.
	Initial	After 5 min.				
60 Product--Control--	60 190	10 10	30.7 29.8	107 112	-----	47.0 63.5

Example 4

65 Employing procedures similar to those described in Example 2, 300 grams (0.38 mole) of a nonylphenol-ethylene oxide adduct containing an average of 13 ethyleneoxy groups in a poly(ethyleneoxy) chain, 90 grams (0.76 mole) of 2,5-dihydrothiophene-1,1-dioxide, and 2 grams (0.087 gram atom) of sodium was heated at 65 to 70° C. for 6 hours. There was recovered 311 grams of crude product containing 76 weight percent 3-[nonylphenoxy]tetrahydrothiophene-1,1-dioxide.

70 The product was admixed with toluene and with solid calcium chloride. The solids were filtered from the mix-

ture and additional calcium chloride was added to the filtrate. After repeating this process, two additional times, and vacuum drying to remove the toluene, the purified product contained 97 weight percent 3-[nonylphenoxy]poly(ethyleneoxy)tetrahydrothiophene-1,1-dioxide.

The properties of both the crude and pure products are tabulated below, together with the properties of the nonylphenol-ethylene oxide adduct.

	Foam Height, mm.		Relative Detergency, Percent	Cloud Point, °C.
	Initial	After 5 min.		
Product:				
Pure	135	5	116	60
Crude	195	5	108	74
Control	220	-----	91	93

From the foregoing table it is clear that the product of this example, particularly when at a purity of 97 percent, has outstanding utility as a low temperature laundry detergent.

Example 5

Employing procedures similar to those described in Example 2, 436 grams (0.164 mole) of the adduct of (a) the reaction product of butanol, ethylene oxide and propylene oxide, the mole ratio of ethylene oxide to propylene oxide being 1/9, said reaction product having a molecular weight of about 1500, and (b) ethylene oxide, said adduct having an average of 34 ethyleneoxy groups in a poly(ethyleneoxy) chain, 1 gram (0.0435 gram atom) of sodium and 58 grams (0.492 mole) of 2,5-dihydrothiophene-1,1-dioxide was heated at 65° C. for 24 hours. There was recovered 435 grams of product which contained 82.9 weight percent sulfone adduct, 10.2 weight percent unreacted butoxy [poly(ethyleneoxy)-poly(propyleneoxy)]poly(ethyleneoxy) adduct, and 6.9 weight percent unreacted dihydrothiophene-1,1-dioxide.

The properties of this product and of the butoxy[poly(ethyleneoxy) - poly(propyleneoxy)]poly(ethyleneoxy) adduct are tabulated below.

	Foam Height, mm.		Relative Detergency, Percent	Wetting Test, gm./l.	Cloud Point, °C.
	Initial	After 5 min.			
Product	130	35	96	3.15	93.4
Control	145	20	106	3.9	>100

Although the relative detergency of the product of this example was lower than that of the parent hydroxyl-containing surfactant, it is readily improved by rebalancing of the hydrophobe-hydrophile ratio by methods known to those skilled in the art.

Example 6

Employing procedures similar to those described in Example 1, a mixture of 464 grams (0.64 mole) of a tridecanol-ethylene oxide adduct containing an average of 12 ethyleneoxy units in a poly(ethyleneoxy) chain, 378 grams (3.20 moles) of 2,5-dihydrothiophene-1,1-dioxide and 10 grams (0.185 mole) of sodium methoxide was heated at 65° C. to 70° C. for 6 hours. There was recovered 427 grams of product which contained 84.85 percent 3-[(tridecoxy)-poly(ethyleneoxy)]tetrahydrothiophene-1,1-dioxide, 13.0 percent unreacted tridecanol-ethylene oxide adduct and 2.15 percent unreacted dihydrothiophene-1,1-dioxide.

The properties of this product and of the tridecanol-ethylene oxide adduct are tabulated below.

5	Foam Height, mm.		Surface Tension, dynes/cm.	Relative Detergency, Percent	Cloud Point, °C.
	Initial	After 5 min.			
10 Product Control	190 225	4 10	28.1 29.4	100 98	74.6 90.0

Example 7

Employing apparatus and procedures similar to those described in Example 1, a mixture containing 448 grams (0.52 mole) of a dodecyl mercaptan-ethylene oxide adduct containing an average of 15 ethyleneoxy units in a poly(ethyleneoxy) chain, 307 grams (2.60 moles) of 2,5-dihydrothiophene-1,1-dioxide and 10 grams (0.185 mole) of sodium methoxide was heated at 65 to 70° C. for 12 hours. There was recovered 398 grams of product containing 81.05 percent 3-[dodecylthiopoly(ethyleneoxy)]tetrahydrothiophene-1,1-dioxide, 16.4 percent unreacted dodecyl mercaptan-ethylene oxide adduct, and 2.55% unreacted dihydrothiophene-1,1-dioxide.

The properties of this product and of the dodecyl mercaptan-ethylene oxide adduct are tabulated below.

30	Foam Height, mm.		Surface Tension, dynes/cm.	Relative Detergency, Percent	Wetting Test, gm./l.	Cloud Point, °C.
	Initial	After 5 min.				
35 Product Control	180 210	4 5	31.3 32.9	102 92	1.13	77.4 89.5

Example 8

Employing procedures similar to those described in Example 2, a mixture of 465 grams (0.75 mole) of a trimethylnonylphenol-ethylene oxide adduct containing an average of 10 ethyleneoxy units in a poly(ethyleneoxy) chain, 442 grams (3.75 moles) of 2,5-dihydrothiophene-1,1-dioxide, and 1.5 grams (0.038 gram atom) of potassium was heated at 65 to 70° C. for 21 hours. There was recovered 429 grams of crude product containing 88.1 percent 3-[trimethylnonylphenoxypoly(ethyleneoxy)]tetrahydrothiophene-1,1-dioxide and 11.9 percent unreacted trimethylnonylphenol-ethylene oxide adduct.

A portion of this crude product was admixed with toluene and then slurried with solid calcium chloride and filtered to remove unreacted trimethylnonylphenol-ethylene oxide adduct. The process was repeated 3 additional times and the toluene was evaporated from the product which contained 94.4 percent 3-tetrahydrothiophyl-1,1-dioxide adduct and 5.6 percent unreacted trimethylnonylphenol-ethylene oxide adduct.

The properties of the pure and crude products and of the trimethylnonylphenol-ethylene oxide adduct are tabulated below.

65	Foam Height, mm.		Relative Detergency, Percent	Cloud Point, °C.
	Initial	After 5 min.		
70 Product	87	3	114	49.0
Pure	145	3	106	57.4
Crude	210	4	99	72.0
Control				

Example 9

Employing procedures similar to those described in Example 1, a nonylphenol-ethylene oxide adduct is reacted with 3-methyl-2,5-dihydrothiophene-1,1-dioxide to produce a product having reduced cloud point and foaming tendency.

Example 10

Employing procedures similar to those described in Example 1, a nonylphenol-ethylene oxide adduct is reacted with 3-ethoxy-2,5-dihydrothiophene-1,1-dioxide to produce a product having reduced cloud point and foaming tendency.

Example 11

Employing procedures similar to those described in Example 1, a nonylphenol-ethylene oxide adduct is reacted with 3-acetoxy-2,5-dihydrothiophene-1,1-dioxide to produce a product having reduced cloud point and foaming tendency.

Example 12

Employing procedures similar to those described in Example 1, a nonylphenol-ethylene oxide adduct is reacted with divinyl sulfone to produce a product having reduced cloud point and foaming tendency.

What is claimed is:

1. A non-ionic surface active compound of the formula:

where Y is an alkyl phenoxy radical said alkyl having from 4-22 carbon atoms, X is a hydrophilic alkyleneoxy chain containing individually one or more alkyleneoxy members selected from the group consisting of methyleneoxy, ethyleneoxy, propyleneoxy and butyleneoxy and mixtures of said ethyleneoxy, methyleneoxy and propyleneoxy members where the atomic ratio of carbon to oxygen is from about 1.5:1 to about 2.1:1, in said mixture, X may be a hydrophilic styreneoxy moiety containing one or more styreneoxy repeating units, R is a member selected from the group consisting of hydrogen or 1-4 carbon atoms alkyl radical, y a lower case may vary from 1 to 6.

2. The compound of claim 1 where y=1.

3. A non-ionic surface active composition of matter of the formula:

where Y is an alkyl phenoxy radical, said alkyl having from 4-22 carbon atoms, X is a hydrophilic alkyleneoxy chain containing individually one or more alkyleneoxy members selected from the group consisting of methyleneoxy, ethyleneoxy, propyleneoxy and butyleneoxy and mixtures of said ethyleneoxy, methyleneoxy and propyleneoxy members where the atomic ratio of carbon to oxygen is from about 1.5:1 to about 2.1:1, in said mixture, X may be a hydrophilic styreneoxy moiety containing one or more styreneoxy repeating units, R is a member selected from the group consisting of hydrogen or 1-4 carbon atoms alkyl radical, y may vary from 1 to 4 and n has a value of at least 0.6y.

15 4. The composition of claim 3 where n has a value of at least 0.75y.

25 5. The composition of claim 3 where said hydrophilic alkyleneoxy chain is a poly(ethyleneoxy) chain.

6. 3 - [nonylphenoxy/poly(ethyleneoxy)]tetrahydrothiophene-1,1-dioxide where said polyethyleneoxy moiety is hydrophylic.

30 7. 3 - [nonylphenoxy/poly(ethyleneoxy)]tetrahydrothiophene-1,1-dioxide where said polyethyleneoxy moiety comprise an average of about 9 to 10.5 ethyleneoxy moieties.

8. 3 - [trimethylnonylphenoxy/poly(ethyleneoxy)]tetrahydrothiophene-1,1-dioxide, where said poly(ethyleneoxy) moiety is hydrophylic.

35 9. 3 - [trimethylnonylphenoxy/poly(ethyleneoxy)]tetrahydrothiophene-1,1-dioxide, said poly(ethyleneoxy) moiety being hydrophilic and comprises an average of about 10 ethyleneoxy moieties.
